ORAL CLEANSING UNIT

Robert C. Gilbert and Tim Cunningham, Mansfield, Ohio, assignors to Westinghouse Electric Corporation, a corporation of Pennsylvania

Filed June 27, 1969, Ser. No. 17,924

Term of patent 14 years

Int. Cl. D24—03

U.S. Cl. D24—1

FIG. 2.

FIG. 1 is a front perspective view of an oral cleansing unit embodying our new design; and

FIG. 2 is a rear perspective view thereof.

We claim:

The ornamental design for an oral cleansing unit, substantially as shown and described.
